UNITED STATES PATENT OFFICE.

EDWARD C. MORRISON, OF FAYETTEVILLE, NEW YORK.

CAR-JOURNAL-POLISHING DEVICE.

Application filed October 8, 1923. Serial No. 667,339.

To all whom it may concern:

Be it known that I, EDWARD C. MORRISON, citizen of the United States, residing at Fayetteville, in the county of Onondaga and

5 State of New York, have invented certain new and useful Improvements in Car-Journal-Polishing Devices, of which the following is a specification.

This invention relates to certain new and 10 useful improvements in car polishing devices and has particular reference to devices of that kind that are portable and capable of being readily applied to or removed from the journals.

15 The primary object of the invention is to generally simplify and improve devices of the above character whereby the same may meet with all of the requirements for a successful commercial use.

20 Another object is to provide a portable car journalling device by means of which the journal may be evenly and uniformly polished.

25 Still another object of the invention is to provide a polishing device capable of being positioned upon a car journal and accurately centered thereon whereby, upon rotation of the device bodily about the journal, the latter will be uniformly polished.

30 A still further object of the invention is to provide means for effectively preventing displacement of the device from the car journal when operatively disposed upon the latter, and to provide means whereby the 35 pressure with which the polishing elements engage the car journal may be effectively regulated to the desired degree.

Other objects will appear as the nature of 40 the invention is better understood, and the same consists in the novel form, combination and arrangement of parts hereinafter more fully described, shown in the accompanying drawings and claimed.

In the drawings, wherein like reference 45 characters indicate corresponding parts throughout the several views:

Figure 1 is a side elevational view of a 50 polishing device constructed in accordance with the present invention and shown applied upon a car journal.

Figure 2 is a transverse sectional view of the device shown in Figure 1, taken to the

right hand side of the pulley in said figure, and

Figure 3 is an elevational view of the inner frame ring of the device. 55

Referring more in detail to the drawings, the usual car journal 5 is enlarged as at 6 at its inner end portion adjacent its connection with the wheel 7 and is provided with an annular outwardly directed flange 8 upon its outer free end. The object of the invention is to provide a device for polishing these journals. 60

The invention embodies a cylinder in the form of a rigid open frame, composed of an outer end disc or ring 9 and an inner ring 10 that are rigidly connected in parallel spaced relation by a plurality of rods 11, 12 and 13, provided in pairs as shown clearly in Figure 2 and positioned adjacent the outer edges of said rings 9 and 10. The rings 9 and 10 are preferably provided with transverse openings in which reduced ends of the rods 11, 12 and 13 are secured in any suitable manner as by riveting or the like, and the rods 11, 12 and 13 are of such length as to position the disc or ring 9 outwardly of and spaced from the flange 8 of the car journal when the ring 10 is disposed to surround the enlarged portion 6 of said journal. 70

The ring 10 is provided with a plurality of radial adjustable screws 14 having operating handles at their outer ends at 15 and provided with rollers 16 upon their inner ends adapted to be adjusted as to contact with the portion 6 of the car journal, whereby the inner end of the device is anti-frictionally mounted upon the portion 6 for three revolutions about the latter. Obviously by proper manipulation of the screws 14, the ring 10 may be adjusted to a position wherein the same is concentric with said journal portion 6. 85

The disc or ring 9 is provided with a relatively small central circular opening 17 in which is loosely fitted a bushing 18 that is flanged at its inner end as at 19, for preventing displacement of the bushing outwardly through the opening 17, and this bushing is internally threaded for adjustable reception of a central screw 21. The screw 21 is threaded through the bushing 18 and has its inner end suitably formed as at 22 to provide 90

anti-frictional engagement thereof with the center point or socket in the outer free end of the journal 5. The outer end of the screw 21 is preferably reduced for the reception of a loop form of handle 23 which is secured upon said reduced portion by means of a nut 24 threaded on the latter outwardly of the portion of the handle which is disposed upon said reduced portion of the screw as shown in Figure 1. The portion of the screw 21 upon which the handle 23 is disposed is preferably of angular form in cross section similar to the openings through the handle so that the screw 21 may be rotated upon rotation of said handle.

Extending inwardly through openings in the disc 9 inwardly of the rod 11 are a pair of pintles 25 that have inturned inner ends as at 26 upon which are journalled anti-friction rollers 27 arranged to bear against the inner surface of the flange 8 whereby this end of the device may freely rotate about the journal and at the same time be held against outward longitudinal displacement from said journal. The pintles 25 are longitudinally adjustable through the ring or disc 9 and this adjustment is secured by means of nuts 28 threaded upon the outer ends of said pintles against the outer surface of the ring or disc 9 as shown in Figure 1.

A plurality of spring arms preferably constructed of strips of resilient metal have their outer ends rigidly attached to the rods 12, and these arms which are indicated at 29 are arranged tangentially of the frame of the device as shown in Figure 2, with their free inner ends suitably engaging the outer surfaces of a pair of opposed polishing strips 30 that are arranged longitudinally of the device and of such length as to engage the major surface of the journal 5. If desired, the polishing elements may be secured to the arms 29 although it is only necessary that said arms be formed with inturned free ends as at 31, to retain the same. Each polishing strip 30 is preferably engaged by a pair of the arms 29 as shown, and said polishing strip will thereby be yieldingly held with a certain amount of pressure, into engagement with the journal. As this pressure will lessen as the polishing strip wears, it is desirable to provide means for adjusting the tension of said arm 29. This is preferably accomplished by means of adjusting screws 32 threaded through the rods 13 and having their inner ends bearing upon the arms 29 as shown, the outer ends of the screws 32 being equipped with handles 33 by means of which they may be manipulated.

The several rods, or if found more desirable, the pair of rods 11 may be utilized for supporting a ring like pulley 34 midway between the ends of the cylinder or

frame of the device to serve as means for facilitating the application of power or rotation to the device whereby the latter may be bodily rotated about the car journal. As shown, the pulley is provided with inwardly projecting lugs 35 that are transversely apertured for slidable reception upon the rods 11, said lugs being provided with set screws 36 by means of which the pulley may be secured in proper position between the end members or rings 9 and 10.

In operation, the device is bodily slipped over the car journal until the ring 10 surrounds the enlargement 12 thereof. The screws 14 are then adjusted inwardly until the rollers 16 engage said enlarged portion 6 of the journal with the ring 10 disposed concentric with the portion 6 and freely rotatable about the latter. The journals 25 are then swung so as to position the in-turned ends 26 thereof behind the flange 8 whereupon said journals are adjusted outwardly to engage the rollers 27 with the inner surface of said flange 8. The center screw 21 is then adjusted inwardly to engage in the socket provided centrally in the outer end of the car journal whereupon the entire device is positioned so that the journal is centered within the same, and whereby the entire device may be bodily rotated with ease about the journal. Power is then applied to the device for rotating the same by means of a belt applied to the pulley 34 and passing around a pulley, (not shown) carried by any suitable drive shaft. Obviously, any suitable gearing may be substituted in lieu of the belt and the pulley 34. With the screws 32 adjusted to the proper degree, the opposed polishing strip 31 will yieldingly engage the surface of the journal with an even pressure, and the journal will be uniformly polished. To remove the device, the pintles 25 are loosened and turned, so as to clear the flange 8, and after the screws 14 are adjusted outwardly, the device may be slid off of the journal by forcing the arms 29 and the polishing strip 30 outwardly to clear said flange 8.

In view of the above, it will be seen that I have provided a very simple, durable and efficient form of journal polishing device, wherein a uniform polishing operation is had, in a simple and expeditious manner.

Minor changes may be made without departing from the spirit and scope of the invention as claimed.

What I claim as new is:

A portable car journal polishing device comprising a pair of end frame members rigidly connected in parallel spaced relation by means of longitudinal frame bars, means to center the inner end of the car journal within one of said end frame members, a center screw engageable in the center socket in the outer end of the car journal for

centering the outer end of said journal within the outer end of the frame, a ring pulley mounted upon certain of said rods for facilitating application of rotation to said frame, longitudinal polishing elements disposed inwardly of the longitudinal frame bar, tangential resilient arms carried by others of said bars and having their free ends urging the polishing strip toward the journals, and means to adjust the tension of 10 said spring arms toward the journal. In testimony whereof I affix my signature.

EDWARD C. MORRISON.
